BASIC ESTERS OF SUBSTITUTED THIENYL
ACETIC ACIDSFrederick F. Blicke, Ann Arbor, Mich., assignor
to Regents of The University of Michigan, Ann
Arbor, Mich., a corporation of MichiganNo Drawing. Application November 3, 1949,
Serial No. 125,380

8 Claims. (Cl. 260—294.3)

1

This invention relates to certain basic-alkyl esters of substituted (alpha-thienyl)acetic acids, the salts of such esters, and pharmaceutical products in which they are employed as active ingredients. This application is a continuation-in-part of my prior-filed copending applications Serial 575,929, filed February 2, 1945, now abandoned, and Serial 695,811, filed September 9, 1946.

One of the principal objects of the present invention is the provision of a series of compounds having utility as pharmaceuticals and particularly as antispasmodic agents. Members of this new group of compounds have been prepared, identified and found to have value as antispasmodics and as the active ingredients in antispasmodic preparations for the relief of muscle spasm as determined by the method of Magnus (Archiv. für die gesammte Physiologie, 1905, vol. 108, pages 1-71). The free basic esters of this group of compounds are usually oily liquids with relatively high boiling points, while the acid or quaternary ammonium salts thereof are usually crystalline solids at ordinary temperatures.

The basic-alkyl esters of the present invention have the following generic formula

wherein R represents a hydrocarbon radical, the carbon chain is straight or branched and contains from 2 to 8 carbon atoms, inclusive, X is hydrogen or hydroxyl radical, and Z is a primary or secondary amine radical.

Within the meaning of R in the above formula I include such hydrocarbon radicals as alkyl radicals, for example, methyl, ethyl, isopropyl, isobutyl, isoamyl, n-hexyl and n-octyl; aryl radicals, such as phenyl, naphthyl, and para-xyenyl; cycloalkyl radicals, such as cyclopentyl and cyclohexyl; cycloalkylalkyl radicals, such as cyclohexylethyl and cyclohexylmethyl; aralkyl radicals, such as phenethyl, phenylmethyl; alkaryl radicals, such as ethylphenyl; alkylcycloalkyl radicals, such as ethylcyclohexyl; alkylcycloalkylalkyl radicals, such as methylcyclohexylethyl; and alkylaralkyl radicals, such as ethylphenylmethyl. Such hydrocarbon radicals preferably contain not more than twelve carbon atoms, regardless of the structure of the substituent.

The primary and secondary amine radicals represented by Z include such radicals as mono-

2

methylamino, monoethylamino, monopropylamino, isopropylamino, monobutylamino, n-octylamino, monocyclohexylamino, diethylamino, diisopropylamino, dibutylamino, dicyclohexylamino, diphenylamino, phenylethylamino, and the like. Z can also represent a saturated nitrogen heteromonocyclic ring such as piperidyl, morpholinyl, pyrrolidyl, piperazinyl and thiazinyl.

10 The compounds included within the scope of the present invention include (a) compounds of the above general formula and (b) salts thereof.

The term "salts" includes acid-addition salts, such as the citrate, tartrate, hydrochloride, hydrobromide, hydrosulfate, and many others, as well as the quaternary ammonium salts, such as the methobromide, ethochloride and ethyl para-toluenesulfonate. The acid salts may be prepared from the free basic ester by treatment with

20 the selected acid, while the quaternary ammonium salts are prepared by treatment of the free basic ester with the desired alkyl halide or aryl sulfonic ester. When the ester is formed by a reaction of an acid and an alkyl halide, or by 25 the reaction of an acid halide and an alcohol, the ester usually precipitates as the hydrohalide salt.

The hydrocarbon substituted thienylaliphatic acids employed as starting materials can be prepared by first reacting thiophene with an alkyl oxalyl halide, e. g., ethyl oxalyl chloride, $\text{CICO}-\text{COOC}_2\text{H}_5$, in the presence of aluminum chloride to produce an alkyl ester of (alpha-thienyl)-glyoxylic acid ($\text{SH}_3\text{C}_4-\text{CO}-\text{COOH}$). The keto acid, obtained by hydrolysis of the ester, is then reacted with a Grignard reagent containing the selected hydrocarbon radical and the resulting complex is decomposed with a suitable acidic reagent, such as HCl , NH_4Cl , NaHSO_4 , et cetera, to produce a substituted thienyl hydroxyacetic acid. This compound can be employed without further modification in the production of the hydroxy-containing basic ester, or it may be reduced, e. g., with stannous chloride, to produce the corresponding hydroxy-free hydrocarbon-substituted thienylacetic acid and thereafter treated to prepare the basic ester.

As an alternative procedure when the hydrocarbon substituent is aromatic, the acyl halide 50 of the alkyl monoester of oxalic acid can first be reacted with a suitable aromatic hydrocarbon such as benzene, biphenyl, naphthalene, et cetera, in the presence of aluminum chloride to produce

the corresponding aromatic substituted glyoxylic acid, the latter hydrolyzed to the free acid, and the acid then reacted with a Grignard reagent derived from a 2-thienyl halide. Decomposition of the magnesium-containing complex with acid and reduction of the hydroxy acid can be carried out as described in the preceding paragraph.

If compounds where X is hydrogen, that is, substituted thienylacetic acids and esters derived therefrom, are desired, it is not essential to pass through the substituted glycolic acids ($X=OH$) as intermediates. A dialkyl 2-thienyl-malonate can be alkylated by the malonic ester syntheses with an R -halide where R is an alkyl or an arylaliphatic hydrocarbon radical. This gives a disubstituted malonic ester,

which, upon hydrolysis and decarboxylation, gives a substituted thienylacetic acid,

The preparations and examples herein will serve to illustrate procedure whereby production of members of this new group of compounds may be accomplished, but are in no way to be construed as limiting.

Preparation 1.—Ethyl (alpha-thienyl) glyoxylate

A mixture of 84 grams (1 mole) of thiophene, 137 grams (1 mole) of ethyl oxalyl chloride and 1500 milliliters of tetrachloroethane was cooled to minus 5 degrees centigrade and 147 grams (1.1 moles) of aluminum chloride was added portionwise thereto with stirring over a period of forty-five minutes. The mixture was stirred for three hours at room temperature and allowed to stand an additional five hours. The mixture was then treated with ice and hydrochloric acid. The organic layer was separated, washed successively with 1:1 hydrochloric acid, water, dilute sodium carbonate solution, and water. The washed layer was then dried with anhydrous sodium sulfate, and fractionally distilled. A yield of 93 grams of ethyl (alpha-thienyl) glyoxylate, boiling at 115-200 degrees centigrade at three millimeters of mercury pressure absolute, was obtained.

Preparation 2.—(Alpha-thienyl) glyoxylic acid

A mixture of 40 grams of ethyl (alpha-thienyl) - glyoxylate, 75 milliliters of ethanol, 58 grams of sodium carbonate monohydrate, and 450 milliliters of water was refluxed for twelve hours. The hot solution was clarified with activated carbon and the alcohol and water removed by distillation under reduced pressure. The residue was cooled and acidified with 1:1 cold hydrochloric acid, extracted with ether, and the ether extract washed with water and evaporated to dryness. Upon recrystallizing the residue from benzene, there was obtained 24 grams of (alpha-thienyl) - glyoxylic acid melting at 89-91 degrees centigrade.

Preparation 3.—Substituted hydroxy acids

A solution of methyl magnesium iodide (prepared by reacting 85.2 grams (0.6 mole) of methyl iodide with 14.4 grams (0.6 mole) of magnesium in 300 milliliters of diethyl ether) was added dropwise and with stirring to 31.2 grams (0.2 mole) of (alpha-thienyl) glyoxylic acid dissolved in 300 milliliters of ether and cooled with a mixture of ice and salt. An immediate vigorous reaction occurred and a precipitate separated. The mixture was stirred for one hour at room temperature, heated to boiling under reflux for two

hours, cooled, and the ether layer decanted and discarded. The granular residue was washed with ether, decomposed with dilute sulfuric acid, extracted with ether, and the ether extract washed with an excess of aqueous twenty per cent sodium carbonate solution. The alkaline wash liquor was clarified with activated carbon, filtered, and the filtrate acidified with dilute sulfuric acid. The precipitate was separated, washed with ether, and dried. After recrystallization from benzene there was obtained 30 grams of methyl - (alpha - thienyl) hydroxyacetic acid melting at 111-113 degrees centigrade.

By substituting cyclohexyl, benzyl, phenyl, para-xenyl, alpha-naphthyl, phenethyl, cyclohexylethyl, isopropyl, n-hexyl or similar magnesium halides, for the methyl magnesium iodide employed in the preparation just described, the corresponding substituted (alpha-thienyl) hydroxyacetic acids are obtained.

In Table I there are given the melting points, empirical formulae, and analyses of representative hydroxy acids employed in accordance with the present invention.

TABLE I

	Melting Point, °C.	Empirical Formula	Sulfur, Per Cent

¹ Recrystallized from benzene.

² Recrystallized from dilute acetic acid.

³ Decomposed.

Preparation 4.—Non-hydroxy acids

In the preparation of thienyl-substituted fatty acids from the hydroxy acids just described, the latter are reduced, preferably with stannous chloride. In a representative operation, 12 grams (0.051 mole) of phenyl-(alpha-thienyl) hydroxyacetic acid, 24 grams (0.106 mole) of stannous chloride dihydrate and 200 milliliters of acetic acid were stirred together. Hydrogen chloride was passed into the mixture with agitation at 15 degrees centigrade. After three hours, the mixture was blown with air to remove acetic acid, the residue mixed with ice-water and filtered. The residue, after washing with water and recrystallizing from fifty per cent acetic acid, weighed 7 grams and consisted of phenyl-(alpha-thienyl) acetic acid.

In Table II there are given the melting points, empirical formulae, and analyses of representative hydrocarbon-substituted (alpha-thienyl) acetic acids employed as reactants in preparing the compounds of the invention. The compounds

were purified by recrystallizing from dilute acetic acid.

TABLE II

	M. P. ° C.	Formula	Sulfur, Per Cent

Other hydrocarbon-substituted (alpha-thienyl)acetic acids prepared as intermediates include isopropyl-(alpha-thienyl)acetic acid, B. P. 163-164° C. (20 mm.), isobutyl-(alpha-thienyl)acetic acid, B. P. 128-130° C. (0.4 mm.), M. P. 60-63° C., and isoamyl-(alpha-thienyl)acetic acid, B. P. 150-155° C. (4-5 mm.). These were prepared by reduction of the corresponding hydroxyacetic acids disclosed in Table I.

In the preparation of the hydrohalides of the basic-alkyl esters of the hydrocarbon-substituted thienyl aliphatic acids, substantially equimolar proportions of a basic-alkyl halide and the hydrocarbon-substituted thienylaliphatic acid are admixed in a suitable solvent, e. g., ethanol or isopropyl alcohol, and the mixture heated until reaction has occurred. This may occur at room temperature or require heating at reflux for some time, e. g., 4 to 16 hours, more or less. The crude salt can be crystallized by dissolving it in a small quantity of warm ethanol, adding diethyl ether until turbidity and thereafter cooling the mixture. The salt separates in crystalline form and is recovered by decantation or filtration. Other acid salts can be obtained in a similar manner from the free basic ester. As the antispasmodic activity of the esters apparently resides in the ester itself, and not in the salt portion of the molecule, any acid can be employed without detracting materially from the effectiveness of the compound, provided only that the anion of the acid employed be reasonably non-toxic, and therefore the salt to be produced is usually chosen primarily with regard to crystallinity and solubility.

As an alternative method of salt formation, a non-hydroxy acid can be converted to the acid chloride, as by heating with thionyl chloride, and the acid chloride then reacted with the selected basic alcohol to form the desired ester hydrochloride. The former method is preferred, however, since higher yields of product are obtained thereby.

Any basic alcohol or basic alkyl halide which meets the requirements of the formula HO-carbon chain-Z or halogen-carbon chain-Z respectively, where "carbon chain" and "Z" have the meanings given hereinabove, can be used in the preparation of the basic esters. In the reaction between a substituted thienylacetic acid or substituted thienylhydroxyacetic acid with a basic alkyl halide, typical halides include 2-diethylamino-1-haloethane, 2 - dimethylamino-1-haloethane, 2 - dipropylamino - 1 - haloethane, 2-diethylamino-1-haloethane, 2 - (N-piperidyl)-1-haloethane, 2-(N-morpholinyl)-1-haloethane, 2-methylamino-1-haloethane, 2 - phenylamino-1-haloethane, 3-diethylamino-1-halopropane, 3-di-

ethylamino-2-halopropane, 4 - diethylamino-1-halobutane, 4-diethylamino-2-halobutane, 5-diethylamino-1-halopentane, 6 - diethylamino - 1-haloheptane, and

5 8 - diethylamino - 1 - haloctane. The halogen atoms can be chlorine, bromine or iodine.

The free basic-alkyl esters can be obtained from the hydrohalides by treatment with aqueous sodium carbonate or other mild alkali, preferably at low temperatures, and thereafter extracting with ether or other suitable solvent. The solvent can then be dried and volatilized in accordance with conventional methods.

To produce quaternary ammonium salts, the free base can be warmed with alkyl halides, such as methyl bromide, ethyl chloride, propyl iodide, et cetera, or with the selected aryl sulfonic ester such as ethyl para-toluenesulfonate, under which conditions the corresponding quaternary salt is 20 usually formed in high yields.

Example 1.—3-diethylaminopropyl phenyl-(alpha-thienyl)hydroxy acetate hydrochloride

A mixture of 3.4 grams of phenyl-(alpha-thienyl)hydroxy acetic acid, 2.2 grams of 3-diethylaminopropyl chloride and 50 milliliters of isopropyl alcohol was refluxed for twelve hours. After 100 milliliters of absolute alcohol had been added to the cold mixture, it was treated with 30 activated charcoal at room temperature, filtered, and the activated charcoal treatment repeated several times. The solvents were removed from the filtrate under reduced pressure, and the residue rubbed under absolute ether. The crude 35 ester hydrochloride (4.6 grams) was recrystallized from a mixture of absolute alcohol and absolute ether; melting point, 142-145 degrees centigrade.

Example 2.—3-diethylaminopropyl phenyl-(alpha-thienyl)acetate hydrochloride

A mixture of 2.7 grams (0.0125 mole) of phenyl-(alpha-thienyl)-acetic acid, 1.7 grams (0.0125 mole) of 3-diethylaminopropyl chloride and 50 milliliters of isopropyl alcohol was refluxed for twelve hours. The cold solution was mixed with 150 milliliters of absolute alcohol, shaken with activated charcoal at ordinary temperature, filtered, the filtrate treated again with 50 activated charcoal, and the mixture filtered. The solvents were removed under reduced pressure, and the residue rubbed under absolute ether. The crude ester hydrochloride (2.5 grams) was recrystallized several times from benzene; melting point 87-89 degrees centigrade.

Example 3.—2-diethylaminoethyl (para-xenyl)-(alpha-thienyl)acetate hydrochloride

A mixture of 4.4 grams (0.015 mole) of (para-xenyl)-(alpha-thienyl)-acetic acid and 5.5 milliliters of pure thionyl chloride was refluxed for one and one-half hours in an oil bath. After the addition of 10 milliliters of dry benzene to the dark brown mixture which contained the acid chloride, the benzene and excess thionyl chloride were removed under reduced pressure. Another 10 milliliters of benzene was added, removed by distillation, and this process repeated several times. The residue was cooled and dissolved in 70 15 milliliters of benzene. To the solution there was added, slowly, 2.0 grams of 2-diethylaminoethanol, and the mixture was refluxed for two hours. The solvent was removed under reduced pressure. The residue, a dark red, viscous mass, 75 was dissolved in 200 milliliters of absolute alcohol

and the solution treated with activated charcoal several times. The solvent was removed under diminished pressure, and the light greenish-yellow, oily ester hydrochloride was rubbed under absolute ether until it became crystalline. It was recrystallized from a mixture of absolute alcohol and absolute ether; melting point 101-103 degrees centigrade.

Example 4.—2-diethylaminoethyl phenyl-(alpha-thienyl) hydroxyacetate hydrochloride

Phenyl-(alpha-thienyl) hydroxyacetic acid (4.86 grams), 2-diethylaminoethyl chloride (2.85 grams) and 75 milliliters of isopropyl alcohol were refluxed for 15 hours. After the addition of 50 milliliters of absolute alcohol to the cold mixture, it was treated with activated charcoal at room temperature, filtered, and the solvents removed under reduced pressure. The residue crystallized when triturated with absolute ether. After recrystallization from absolute alcohol, the hydrochloride melted at 181-182 degrees centigrade.

Example 5.—2-diethylaminoethyl phenyl-(alpha-thienyl) acetate hydrochloride

A mixture of 4.36 grams of phenyl-(alpha-thienyl) acetic acid, 2.75 grams of 2-diethylaminoethyl chloride and 40 milliliters of isopropyl alcohol was refluxed for 15 hours. Isopropyl alcohol was removed under reduced pressure, the residue dissolved in absolute alcohol, decolorized with activated charcoal, filtered and alcohol removed by distillation. The residue was rubbed under absolute ether whereupon crystallization began. The hydrochloride melted at 98-100 degrees centigrade.

Example 6.—2-diethylaminoethyl cyclopentyl-(alpha-thienyl) hydroxyacetate hydrochloride

An aqueous solution of 13.8 grams of 2-diethylaminoethyl chloride hydrochloride was neutralized with sodium hydroxide, and the free 2-diethylaminoethyl chloride was extracted with ether. The ether extracts were dried over anhydrous magnesium sulfate, filtered, and the filtrate was added to a solution of 13.6 grams of cyclopentyl-(alpha-thienyl) hydroxyacetic acid in 100 milliliters of isopropyl alcohol. The mixture was then distilled through a 25-centimeter Vigreux-type column until the temperature of the vapors reached 80 degrees centigrade. The residual solution was refluxed overnight and then transferred to a beaker along with 350 milliliters of isopropyl alcohol. The crystalline hydrochloride had meanwhile separated out, and this was filtered, washed with isopropyl alcohol, ether and then dried, giving 23 grams, melting point 172-173.5 degrees centigrade. Recrystallization from 400 milliliters of isopropyl alcohol gave 20.3 grams of 2-diethylaminoethyl cyclopentyl-(alpha-thienyl) hydroxyacetate hydrochloride, melting at 174-175 degrees centigrade; deep yellow-orange color with concentrated sulfuric acid.

In Table III are given the melting points (and in some cases, the boiling point) of some esters and salts thereof which are representative of the present invention. They were prepared from the corresponding acids and alcohols by the method described in the preceding examples. The intermediate acids are all disclosed in Tables I and II.

A preferred embodiment of the present invention resides in compounds of the formula

and the carbon chain is a normal chain and contains between 2 and 8 carbon atoms.

3. A basic ester having the formula

wherein X and the carbon chain have the values 35 previously given, and wherein R is a hydrocarbon radical of between 1 and about 15 carbon atoms selected from the group consisting of alkyl, aryl, cycloalkyl, aralkyl and cycloalkyl alkyl; and Z is a member of the group consisting of dialkyl-amino and saturated nitrogen heteromonocyclic radicals, which compounds have exhibited exceptional antispasmodic activity. Particularly effective are compounds wherein R is carbocyclic (aryl or cycloalkyl). Some of the compounds 45 also exhibit local anesthetic and mydriatic effects.

It is to be understood that many variations can be made without departing from the spirit and scope of the invention, and that I am to be limited only by the appended claims.

I claim:

1. A compound selected from the group consisting of (a) basic-alkyl esters of the formula

wherein R represents a hydrocarbon radical having from 1 to 12 carbon atoms, the carbon chain is straight or branched and contains from 2 to 8 carbon atoms, inclusive, X is selected from the group consisting of hydrogen and hydroxy radicals, and Z is selected from the group consisting of lower-alkylamino, lower-dialkylamino, cycloalkylamino, dicycloalkylamino, phenyl-lower-alkylamino, piperidyl, pyrrolidyl and morpholinyl; (b) acid-addition salts and (c) quaternary ammonium salts thereof.

2. A basic ester having the formula

in which R represents a carbocyclic hydrocarbon radical having not more than 12 carbon atoms 75

and the carbon chain is a normal chain and contains between 2 and 8 carbon atoms.

3. A basic ester having the formula

in which R represents a carbocyclic hydrocarbon radical, having not more than 12 carbon atoms, the carbon chain is a normal chain and Z is an 40 N-piperidyl radical.

4. An acid-addition salt of 2-(N-piperidyl)-ethyl alpha-phenyl-alpha(2-thienyl)hydroxyacetate having the formula

5. An acid-addition salt of 2-diethylaminoethyl alpha-cyclohexyl-alpha(2-thienyl)hydroxyacetate having the formula

6. An acid-addition salt of 2-diethylaminoethyl alpha-cyclopentyl-alpha(2-thienyl)hydroxyacetate having the formula

7. An acid-addition salt of 2-diethylaminoethyl

11

alpha - phenyl - alpha(2 - thiienyl)acetate having
the formula

8. An acid-addition salt of 2-diethylaminoethyl 10
alpha - phenyl - alpha(2-thienyl)hydroxyacetate
having the formula

5

12
